UNITED STATES PATENT OFFICE.

PATRICK L. HUSSEY, OF DAYTON, OHIO.

BICYCLE TUBE-CLAMP.

SPECIFICATION forming part of Letters Patent No. 653,243, dated July 10, 1900.

Application filed September 25, 1899. Serial No. 731,585. (No model.)

To all whom it may concern:

Be it known that I, PATRICK L. HUSSEY, a citizen of the United States, residing at Dayton, in the county of Montgomery and State 5 of Ohio, have invented certain new and useful Improvements in Bicycle Tube-Clamps; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to improvements in bicycles, and has particular reference to the handle-bar and stem, as hereinafter fully described in connection with the accompanying drawings, of which—

20 Figure 1 is a sectional elevation through the handle-bar and stem. Fig. 2 is a section taken on a plane at a right angle to Fig. 1 through the longitudinal center. Fig. 3 is a section through the upper end of the handle- 25 bar stem, showing a modification in the means for attaching the handle-bar. Fig. 4 is a top view of the central portion of the handle-bar. Fig. 5 is an elevation of the lower end of the handle-bar stem. Fig. 6 is 30 a sectional view on the line $\alpha\alpha$ of Fig. 2 looking up. Fig. 7 is a view showing one-half of the handle-bar clamp. Fig. 8 is a top view of the stem as shown in Figs. 1 and 2; Fig. 9, views of the clamp and washer used in connection with the stem shown in Fig. 3; Fig. 35 10, an end view of the expander and contractor.

The said invention has specific reference to means for frictionally binding the handle- 40 bar tube to the fork-tube or the saddle-post in the frame of the bicycle.

1 designates a clamp which is split or divided through its longitudinal center on one side and is adapted to compress the central 45 portion of the handle-bar 2. The split side of the clamp 1 terminates in an eye 3, which fits over the top of the tube 4 and binds against the shoulder 5.

6 is a pin projecting from the upper end of 50 the tube 4 and penetrating an opening 7 in the clamp. This pin prevents the clamp and handle-bar from turning laterally on the tube.

The clamp is secured in position on the tube by a nut 8, which screws onto the reduced end of the tube and binds the said clamp 55 against the shoulder 5. Other means are shown in Figs. 3 and 9 for preventing the said clamp from turning on the tube, which consist of tapering the metal surrounding the eye of the clamp, as at 10, and correspondingly tapering the shoulder on the tube, as at 60 11, and in further providing a screw-washer 12, which fits into the upper side of the eye and conforms to the taper thereof.

The parts when tightened by the nut 8 65 bind by friction against the shoulder on the tube. On changing the handle-bar from a drop to a raised position, and vice versa, the nut 8 is removed and the clamp with the handle-bar is lifted off the tube and replaced 70 in a reversed position, and said nut is then replaced and retightened. This change in the positions of the handle-bar does not alter the relative positions of said handle-bar and the seat. The handle-bar may thus be supported 75 in a raised or lowered position, either forward or in the rear of the handle-bar tube. The change from the forward to the rearward positions would of course vary the distance of the handle-bar from the seat; but changing 80 from a drop to a raised bar, and vice versa, in either case would not interfere with the relative positions of the handle-bar and tube 4. When the clamp is secured to the tube, the handle-bar is tightly compressed by said 85 clamp and the connection between the two is most secure. The tube is secured in position in the fork-tube 13 by an internal expander and contractor consisting of a wedge-shaped block 14, which lies across the interior of the 90 stem with its ends projected into openings 15 cut in the opposite sides of the stem.

As shown in Figs. 1 and 5, the shape of the openings 15 corresponds to the shape of the block 14; but said openings are essentially 95 somewhat larger than the block in order that the latter may move up and down therein to expand or contract the tube 4, as the case may be. The dotted lines on each side of the tube, Fig. 5, indicate the expansion and 100 contraction lines of the slotted portion of the tube 4 under such movement. The tube on both sides is provided with longitudinal slots 16 and 17, which extend from the openings

15. The lower slot 17, it will be seen, does not extend entirely to the lower end of the tube. This is essential, as the tube may always enter the head of the bicycle without difficulty, which would be otherwise if said lower slots extended entirely through to the end of said tube, for reasons which are apparent. The tube is expanded to bind it by the tapering sides 18 of the block engaging the 10 corresponding sides of the openings 15 when said block is moved down, and the necessary contraction is given said tube to release said engagement by the inner tapering sides 19 of the block engaging with the corresponding 15 sides 20 of said opening on the upward movement of said block, the downward movement expanding and the upward movement contracting the tube.

The block 14 is properly secured to the lower 20 end of a rod 21, the upper portion of which has a screw-threaded engagement with the upper end of the tube and terminates in an integral head or nut 22 above the extreme upper end of the stem, by means of which 25 the said rod may be screwed up or down to impart the necessary movement to the block without interfering with the clamp or nut securing the handle-bar.

Having described my invention, I claim—
30 1. In a bicycle, the combination of a tube having openings on opposite sides, the said openings having inner and outer tapering sides, slots extending longitudinally on opposite sides of the tube and terminating at said 35 openings, a block inclosed within said tube and conforming to the shape of the openings, in cross-section, and a rod to which said block is connected and by means of which said block is moved in either direction to expand 40 or contract the tube, substantially as described.

2. In a bicycle, the combination of a tube having uniform openings on opposite sides, said openings having inner and outer tapering sides, slots extending longitudinally above and below said openings, the lower slot being terminated at a point above the lower extremity of the tube, a block inclosed within said tubes with its ends projected into the openings therein, the said block having inner and outer contraction and expansion surfaces which engage with the similar surface of the said openings, and a rod to which said block is secured, the said rod projecting above the upper end of the tube, whereby the block 50 may be raised or lowered in the tube to contract or expand said tube, substantially as described.

3. In a bicycle, the combination of a tube having the upper end thereof reduced, made 60 solid and provided with a screw-threaded opening, said reduced portion being adapted to receive a handle-bar clamp, and tapering slots on opposite sides in the lower portion of said tube, with slots extending from said tapering openings, an expansion-block inclosed within said tube with its ends projected into said tapering openings, and a rod having its lower ends attached to said expansion-block, and the upper end of said rod having a screw-threaded engagement with the solid screw-threaded end of the stem, and a rigid head on said rod by means of which said rod may be moved up or down to raise or lower the expansion-block, substantially as and for the 70 purposes specified.

In testimony whereof I affix my signature in presence of two witnesses.

PATRICK L. HUSSEY.
